UNITED STATES PATENT OFFICE.

ROBERT CARL RAHM, OF WYOMISSING, PENNSYLVANIA, ASSIGNOR TO BERKS ENGINEERING COMPANY INC., OF READING, PENNSYLVANIA, A CORPORATION OF PENNSYLVANIA.

LACE-BRAIDING MACHINE.

Application filed December 5, 1919. Serial No. 342,664.

To all whom it may concern:

Be it known that I, ROBERT CARL RAHM, a citizen of the United States, residing at Wyomissing, in the county of Berks and State of Pennsylvania, have invented certain new and useful Improvements in Lace-Braiding Machines, of which the following is a specification.

My invention relates particularly to lace-braiding machines, and consists in improved carrier-drive mechanism, therefor as hereinafter fully described in connection with the accompanying drawings and clearly defined in the subjoined claims.

Fig. 1 is a plan view of a portion of a lace machine showing three adjacent intersecting race-circles with my improved rotary quoits and an engaged carrier base in position.

Fig. 2 is a corresponding sectional elevation mainly on the line 2—2 of Fig. 1.

Figs. 3 and 4 are sectional plan views on the lines 3—3 and 4—4 respectively of Fig. 2.

Fig. 5 is a sectional view on the lines 5—5 of Figs. 1, 2, 3 and 4.

Figs. 6, 7 and 8, 9 are detail views of the two quoit parts; and Fig. 10 is a separate view of the clutch lever and stop device.

The drawing illustrates the application of my invention to a simple form of so-called "single-thread" lace braiding machine in which a carrier is intermittently swung a half revolution in each of a series of intersecting race-circles which are grouped around a braiding center and provided with a rotary carrier-engaging plate or quoit in each race-circle.

The arranging of these intersecting race-circles in a curved series, as indicated in Fig. 1, results in the formation in each race-circle of a shorter inner race-way arc 10, and a longer outer arc 11; and an important feature of my invention consists in employing a carrier-engaging quoit comprising separate parts having not only a joint rotary movement, but also a limited relative movement which enables the automatic neutralizing of this difference in the race-circle arcs. The invention further consists in the improved clutch-control drive mechanism hereinafter fully described.

Between the top plate 15 and bottom plate 16 extend the usual series of race-circle posts

17, upon which are mounted the continuously rotated drive gears, 18, 18. Each of these 55 gears is thrown into connection with its carrier engaging quoit by means of a clutch mechanism, which in the construction indicated, provides for axially moving the gear itself by means of an engaging clutch arm or 60 lever 20 carried by a pattern-operated clutch bar 21.

The two quoit parts shown comprise approximately half-circle plate portions, 25, 25^a, having meeting edges which are radial 65 but which depart from a common diametral line so as to leave a gap 26 between them equal to the difference between the lengths of the outer and inner race-circle arcs 11 and 10; the opposite arcuate arms of each plate 70 portion which are bounded by the arced carrier-engaging recess 30, being each equal, as shown, to one-half of the shorter inner arc 10 of the race-circle; so that when the two plate portions are set in a race-circle 75 with the gap 26 between them as shown to the left in Fig. 1, they extend the full length of the long outer arc 11 as well as of the shorter inner arc 10, while the recesses 30, 30 complete the adjoining circles. The 80 lower end of each carrier is formed with a flanged race-way shuttle portion 31, of lenticular cross-section having opposite convex lines corresponding with the similarly curved walls of the race-circles and of a 85 recess 30, so that the engaged carrier is maintained in fixed radial relation to each center around which it is traversed, and always has extended wall contact.

Each of the quoit parts 25, 25^a, is separately mounted on its post 17 so as to be capable of an independent rotary movement sufficient to open or close the gap 26 as adjacent plate portions are successively swung close to the outer race-circle arc 11 95 or the inner arc 10; the part 25 having spaced-apart post-encircling band portions 35, 35^a, and the part 25^a a similar band portion 35^b.

When the drive gear 18 is raised by the 100 clutch lever 20, its clutch tooth 41 strikes a tooth 42 or 43 of a quoit part 25 or 25^a as the case may be, so as to first turn such part alone with the gear until the gap 26 is closed, and then turn both parts until such joint 105 rotation is automatically stopped after a

half revolution. This automatic stopping is effected by means of a lateral projection 45 on the fixed post 17, which is arranged to engage a cam projection 46 on the rotating gear so as to positively force the latter out of driving engagement with the quoit; and this automatic clutch-disengaging movement is made to also effect the locking of the stopped quoit parts in proper rest positions, by providing the clutch lever 20 with a lock member 50 arranged to enter the gap 26 between the quoit parts when the gear is disengaged from the latter. This lock member 50, after it has been raised by the pattern operated bar 21 carrying with it gear 18, rides upon flange portions 27, 27^a of the turning quoit parts so as to hold said gear in upper position for a determined time; and when it is lowered by the automatically effected disengaging movement of the drive gear 18 occupies the gap 26 so as to insure the proper relative positioning of the quoit parts while at the same time properly stopping and holding them.

25 My parted quoit construction effects a great improvement in the operation of the machine, and provides for positive control and guidance of the carriers; and the quoit operating mechanism is at all times positively actuated and controlled. The particular application of my improvements, and the detail construction specifically set forth, may be readily varied within the scope of the invention as defined in the claims.

35 What I claim is:

1. In a lace braiding machine having a circularly arranged series of intersecting race-circles, rotary quoits in said race-circles each comprising relatively movable carrier-engaging parts having opposite arcuate portions equal to one half the inner arc of its race-circle.
2. In a lace braiding machine having a circularly arranged series of intersecting race-circles, rotary quoits in said race-circles each comprising carrier engaging parts capable of relative rotary movement equal to the difference between the outer and inner race-circle arcs.
3. In a lace braiding machine having a circularly arranged series of intersecting race-circles, rotary quoits in said race-circles each comprising carrier engaging parts capable of relative rotary movement equal to the difference between the outer and inner race-circle arcs, and a quoit engaging stop adapted to lock said parts against relative rotary movement.
4. In a lace braiding machine having a circularly arranged series of intersecting race-circles, rotary quoits in said race-circles

each comprising two carrier engaging parts capable of relative rotary movement equal to the difference between the outer and inner race-circle arcs.

65

5. In a lace braiding machine having a circularly arranged series of intersecting race-circles, rotary quoits in said race-circles each comprising two carrier engaging parts capable of relative rotary movement equal to the difference between the outer and inner race-circle arcs, and a quoit engaging stop adapted to lock said parts against relative rotary movement.

70

6. In a lace braiding machine having a circularly arranged series of intersecting race-circles, rotary quoits in said race-circles each comprising two approximately half circle carrier-engaging parts capable of relative rotary movement in having contiguous arcuate portions jointly equal in extent to the inner race-circle arc.

75

7. In a lace braiding machine, a race-circle quoit comprising jointly and relatively rotatable parts each having a carrier-engaging disc portion and a post encircling sleeve portion.

80

8. In a lace braiding machine, a race-circle quoit comprising two jointly and relatively rotatable parts each having an approximately half circle carrier-engaging disc portion and a post encircling sleeve portion.

85

9. In a lace braiding machine, a race-circle carrier-engaging quoit comprising jointly and relatively rotatable parts.

90

10. In a lace braiding machine, a race-circle carrier-engaging quoit comprising two jointly and relatively rotatable parts.

95

11. In a lace braiding machine, a race-circle carrier-engaging quoit comprising two jointly and relatively rotatable parts, a clutch-controlled drive gear adapted to engage and disengage one of said parts and a clutch lever adapted to lock said parts against rotation when said gear is disengaged.

100

12. In a lace braiding machine, a race-circle carrier-engaging quoit comprising two jointly and relatively rotatable parts, a clutch-controlled drive gear, and a clutch lever arranged to lock said quoit against rotation and to release the same.

110

13. In a lace braiding machine having a series of overlapping race-circles, rotary quoits in said circles each comprising relatively rotatable parts each of which has an edge portion recessed to the curvature of an adjacent race-circle, and carriers having oval-section shuttle portions corresponding with said recesses.

115

In testimony whereof I affix my signature.
ROBERT CARL RAHM.
